UNITED STATES PATENT OFFICE.

MICHAEL HASTINGS, OF BROOKLYN, NEW YORK, ASSIGNOR TO THOMAS W. WILLIAMS AND CHARLES A. WILLIAMS, OF NEW LONDON, CONNECTICUT.

PRESSURE-REGULATOR.

SPECIFICATION forming part of Letters Patent No. 409,200, dated August 20, 1889.

Application filed March 9, 1889. Serial No. 302,600. (No model.)

To all whom it may concern:

Be it known that I, MICHAEL HASTINGS, of Brooklyn, Kings county, and State of New York, have invented certain new and useful 5 Improvements in Pressure-Regulators, of which the following is a specification, reference being had to the accompanying drawings.

My invention relates specially to the regulation of the air-pressure as developed by air- 10 compressors or other pumping apparatus by the control of the admission of steam or other operating medium to the power-cylinder of said air-compressors or pumping apparatus. In the development and control of the 15 compressed air it is essential that provision, reliable and delicate in its operation, be made whereby the supply of operating medium be under the immediate automatic control of the resulting compression of air, so that a 20 regular and equable pressure be maintained under all conditions and demands.

My invention consists in the arrangement, construction, and combination of the several parts or portions constituting the pressure- 25 regulator, as hereinafter shown and described.

In the accompanying drawings, Figure 1 represents a pressure-regulator embodying my improvements. Fig. 2 represents a cross-section on the horizontal center line of ad- 30 mission and discharge connections of supply- valve for operating medium.

Similar letters of reference designate like parts or portions in all figures.

The letter A designates the valve-chamber 35 of a steam-supply valve forming a portion of the pressure-regulator.

B designates a steam-supply pipe or connection leading from boiler or generator to chamber A.

40 C designates a steam pipe or connection leading from chamber A to pumping-engine or compressor cylinders.

D designates an annular valve operated by a stem E.

45 F designates a guide for said annular valve D and its stem E.

G designates a lever attached to stem E for the operation of the valve D.

H designates a vibrating fulerum upon which lever G operates. 50

I designates a resistance-spring to regulate and steady the movements of the valve D. d designates a circular seat for the valve D. Holes or perforations d' are made in the disk of valve D to balance the pressure upon the 55 same to as great an extent as possible.

As a means for withdrawing the condensed steam or water from the chamber A, a small hole or opening a' is made in the bottom of said chamber, and a plug, drain-pipe, or cock 6c is inserted after the usual manner.

The letter J designates a cylinder into which compressed air is admitted to move an inclosed piston K, said piston being attached to and operated by a rod L. 65

M designates a lever attached to stem L for controlling the movement of piston K by any air-pressure brought to bear upon it.

N designates a fulcrum, fixed or vibrating, upon which the lever M operates. 70

O designates a guide for lever M. 75 P designates a resistance-spring inclosed in a casing Q and operating by means of rod R to regulate and steady the movement and lift of lever M and weight S. Rod T connects the levers G and M of the steam and air systems together for mutual and joint control and action.

U designates the compressed-air inlet for cylinder J. 80

In the regular operation of this pressure-regulator communication with compressed-air tank is maintained through U with the interior of cylinder J, the increased or decreased pressure coming upon piston K tending to 85 raise or lower the same in accordance with the position and volume of weight S. To regulate to a nicety the air-pressure per square inch upon the piston K, a resistance-regulator composed of spring P, casing Q, 90 and rod R is adjusted to receive a portion of the leverage pressure of weight S, and so by the closing or opening of spring P a delicate increase or decrease of the pressure-bearing capacity per square inch is effected. Again, 95 in the regular operation the steam or equiva-

lent medium for operating the compressors or pumps passes in at pipe-connection B, thence through the valve-chamber A, as shown by the arrows, and out at pipe-connection C to the compressor or pumps for use.

In the combined movement of the air and steam portions of the system an increase of pressure per square inch below the piston K develops an upward movement of the said piston, which movement is transmitted by means of rod L to the lever M to raise the said lever and its weight S. The upper movement of lever M is transmitted through rod T to steam-valve lever G, which in its turn 15 raises stem or rod E, lifting annular valve D to come in contact with its seat *d* to cut off the supply of steam operating compressors or pumps. Owing to the extended circular opening but little movement of the valve is necessary to open or close or increase or decrease the supply of steam to the power-cylinders of the compressors or pumps. A decreased pressure per square inch would effect a reverse movement of the levers and connections and open 20 the valve D. It will be noted upon examination that a reliable operation of the system can be effected without either one or both of the spring-regulators I and P; but the movements of the parts would be of the jumping 25 character, whereas with the additions of these spring portions a very delicate and quite sensitive movement is the result, the adjusting-screws I' and P' assisting in such results.

Any of the well-known lift-valves may be 30 used in lieu of the steam-valve here shown; but I prefer the one shown on account of delicate action and quick opening and closing.

What I claim as new, and desire to secure by Letters Patent, is—

40 1. The combination of a valve-chamber lo-

cated within the line of steam-pipe supplying an air-compressor or pump-cylinder with steam, a perforated annular valve and valve-stem moving within said valve-chamber, a special circular valve-guide operating within 45 said perforated annular valve, a lever for operating said perforated valve and its stem, an air-pressure cylinder and inclosed piston and rod located within the line of air-pipe communicating with the compressed-air receiver 50 or tank, a weighted lever operated by said piston and rod, and a communicating rod attached at one end to the lever operating the steam-valve and its stem and at the other end to the lever operated by said piston and rod 55 of said air-pressure cylinder, substantially as and for the purposes set forth.

2. The combination of a valve-chamber having an annular valve and operating-stem of the character herein shown and described located within the line of steam-pipe supplying an air-compressor or pump cylinder with steam, a lever for operating said valve and stem, a resistance-spring acting upon said lever, an air-pressure cylinder and 60 inclosed piston and rod located within the line of air-pipe communicating with the compressed-air receiver or tank, a weighted lever operated by said piston and rod, a spring-regulator acting upon said lever, and a communicating rod attached at one end to the lever operating the steam-valve and stem and at the other end to the lever operated by said piston and rod of said air-pressure cylinder, 65 substantially as shown and described.

MICHAEL HASTINGS.
